RAZOR

Neil A. Holsclaw, Chicago, Ill., assignor of one-half to Fred E. Sudlow, Rock Island, Ill.

Application July 25, 1942, Serial No. 452,283

8 Claims.

(Cl. 30—90)

This invention relates to improvements in mechanized or dry shavers.

It is a known fact that in all mechanized or dry shavers substantially all of the clippings of whiskers or hairs lodge in the cutter head. Usually such clippings are removed from the interior of the head by means of a brush, but it has been found from experience that this manner of cleaning is ineffective because the brushes so employed wear out quickly or are readily lost. Also, at least one of the large commercial mechanized razor manufacturers has recommended that no brushes be used because of the inherent danger of mutilating the cutting head, which they found from experience frequently occurs. It was to provide a means for automatically removing the clippings from the interior of the shaving head that this invention was designed.

The main objects of this invention are to provide a cleaning element for automatically removing hair clippings from the interior of a shaving head of a mechanized or dry razor; to provide means of this character which may be readily inserted into the interior of the head of a mechanized razor without altering or changing the usual razor head itself; to provide means of this character which is loosely positioned within the razor head and arranged to vibratably reciprocate by the frictional contact of the means against the inner movable cutter member of the razor head; and to provide an automatic cleaner for mechanized or dry shavers which is simple in construction, readily adapted to a mechanized razor head, and inexpensive to manufacture.

A specific embodiment of this invention is shown in the accompanying drawing in which:

Figure 1 is a side view of a mechanized razor, a part thereof being shown broken away to illustrate the seating of a razor head.

Fig. 2 is a vertical cross-sectional view taken on the line 2—2 of Fig. 1.

Fig. 3 is a cross-sectional view taken on the line 3—3 of Fig. 2.

Figs. 4, 5 and 6 are top, side and end views respectively of the cleaner element to which this invention is specifically directed.

As the modern tendency is to close up the ends of the outer stationary cutter and provide some means for collecting the clipped hairs, I have shown this type of razor case or housing in the drawing. The case 1 is provided with the usual motor or vibrator, not shown, and is cut out at its upper end to receive and form a seat for the stationary outer or face bearing elongated U-shaped cutter 2 and inner or mov-

able U-shaped cutter 3. The outer cutter 3 is seated in the casing between the two end members 4 and 5 respectively and the outer cutter is usually removably secured therein by suitable means such as screws or the like, not shown. The inner cutter 3 is arranged to reciprocate within the outer cutter 2. Reciprocable motion is imparted to the inner cutter 3 by the motor or vibrator, not shown, through the pivoted arm 6, the upper end of which is loosely journaled to the lower medial portion 7 of the inner cutter 3.

The inner cutter is adapted to be reciprocated within the outer stationary cutter 2 by the motor or vibrator, not shown, and to eliminate as much friction as possible between the inner and outer cutters, I employ a ball bearing 8 seated in the bottom of the outer cutter 2. The inner cutter 3, provided with track 9, rides on said ball bearings 8.

The automatic cleaner device to which this invention is directed comprises a metal wire or band bent substantially rectangular in shape but with the ends thereof projecting outwardly to blunt points 10 and 11 (see Figs. 3 and 5). In the form shown the upper and lower or substantially parallel long side members 12 and 13 of the cleaner are bent in zigzag or undulated form and are also transversely arcuate in shape. The zigzag or undulated form is applied to the upper and lower members in such a manner that the undulations occur in two planes that are normal to each other. For example, in the horizontal plane the undulations travel to and fro laterally and in the vertical plane the undulations travel up and down along the length of the upper and lower members.

The cleaner is inserted in the razor head and within the inner movable cutter. It can now be seen that as the inner cutter is reciprocated the cleaner will vibrate and reciprocate by the mere frictional engagement of the cleaner against the walls of the reciprocating cutter 3 to thereby effectually agitate the hair clippings falling within the interior of the inner cutter. In the form shown one end of the inner cutter is provided with an end wall 14 thereby, when the inner cutter is reciprocating, causing the clipped hairs to be agitated and discharged through the open end of the inner cutter into the clipping chamber 15. I have provided a shiftable cover plate 16 to prevent the clipped hairs from falling out of the chamber until the cover plate is removed.

It is to be understood that the cleaner may be modified to assume numerous shapes and forms,

for instance, the blunt points may be eliminated, the undulations may be varied etc.

Although but one specific embodiment of this invention is herein set forth, it is to be understood that some of the details may be altered or omitted without departing from the spirit of the invention as defined by the following claims.

I claim:

1. In a mechanized shaving device having a shear head comprising an outer cutter and a hollow inner cutter of substantially inverted U-shaped form and having open ends, means for reciprocating said inner cutter, in combination with a member loosely contained within said shear head and adapted to vibrate therein through contact with said inner cutter when said inner cutter is being reciprocated to agitate the clipped hairs entering said inner cutter and discharge them therefrom.

2. In a mechanized shaving device having an outer cutter, a hollow inner cutter having side walls, one end of the cutter being open ended, and means for reciprocating said inner cutter, in combination with a member loosely contained in said inner cutter and adapted to vibrate therein through contact with said walls of said inner cutter when said inner cutter is being reciprocated to agitate the clipped hairs entering said inner cutter.

3. In a mechanized shaving device having an outer cutter, a hollow inner cutter having top, bottom and side walls, and being open ended, and means for reciprocating said inner cutter, in combination with an elongated wire loop, loosely contained in said inner cutter and adapted to vibrate therein through contact with said walls of said inner cutter when said inner cutter is being reciprocated to agitate the clipped hairs entering said inner cutter.

4. In a mechanized shaving device having an outer cutter, a hollow inner cutter having side walls, and of substantially inverted U-shaped form and means for reciprocating said inner cutter, in combination with an elongated wire loop, loosely contained in said inner cutter and adapted to vibrate therein through contact with said walls of said inner cutter when said inner cutter is being reciprocated to agitate the clipped hairs entering said inner cutter, the long side

members of said loop being formed with undulations.

5. In a mechanized shaving device having an outer cutter, an inner cutter of substantially inverted U-shaped form and means for reciprocating said inner cutter, in combination with a member loosely contained in said inner cutter and adapted to vibrate therein through contact with the walls of said inner cutter when said inner cutter is being reciprocated to agitate the clipped hairs entering said inner cutter.

10 6. In a mechanized shaving device having an outer cutter, an inner cutter of substantially inverted U-shaped form and means for reciprocating said inner cutter, in combination with an elongated wire loop, loosely contained in said inner cutter and adapted to vibrate therein through contact with the walls of said inner cutter when said inner cutter is being reciprocated to agitate the clipped hairs entering said inner cutter, the long side members of said loop being formed with undulations and transversely arcuate in shape.

15 7. In a mechanized shaving device having a shear head comprising an outer cutter and an inner cutter of substantially inverted U-shaped form, means for reciprocating said inner cutter, in combination with an elongated member loosely contained in said shear head and adapted to vibrate therein through contact with said inner cutter when said inner cutter is being reciprocated to agitate the clipped hairs entering said inner cutter and discharge them therefrom, the parallel long sides of said member being formed with undulations occurring in two planes which are normal to each other.

20 8. In a mechanized shaving device having an outer cutter, an inner cutter of substantially inverted U-shaped form and means for reciprocating said inner cutter, in combination with an elongated wire loop, loosely contained in said inner cutter and adapted to vibrate therein through contact with the walls of said inner cutter when said inner cutter is being reciprocated to agitate the clipped hairs entering said inner cutter, the long side members of said loop being bent in a zigzag shape, the short sides of said loop being bent to form blunt pointed ends.

NEIL A. HOLSCLOW.
